US0D1020345S

(12) **United States Design Patent** (10) Patent No.: **US D1,020,345 S**
(45) Date of Patent: ** Apr. 2, 2024

(54) **COFFEE MAKER**

(71) Applicant: **SharkNinja Operating LLC**,
Needham, MA (US)

(72) Inventors: **Dan Kestenbaum**, Brookline, MA
(US); **Benjamin Sharp**, Cumbria (GB)

(73) Assignee: **SharkNinja Operating, LLC**,
Needham, MA (US)

(**) Term: **15 Years**

(21) Appl. No.: **29/870,009**

(22) Filed: **Jan. 13, 2023**

(57) **CLAIM**

The ornamental design for a coffee maker, as shown and described.

DESCRIPTION

FIG. 1 is a perspective view of a coffee maker, showing our new design;

FIG. 2 is a front view thereof;

FIG. 3 is a rear view thereof;

FIG. 4 is side view thereof;

FIG. 5 is another side view thereof;

FIG. 6 is a top view thereof;

FIG. 7 is a bottom view thereof; and,

FIG. 8 is another perspective view thereof.

The broken lines in the drawings are depict portions of the coffee maker that form no part of the claimed design.

1 Claim, 8 Drawing Sheets
